UNITED STATES PATENT OFFICE.

JOSEPH W. PIPER, OF LOWELL, MASSACHUSETTS.

GRATE FOR FURNACES AND BOILERS.

Application filed February 1, 1922. Serial No. 533,463.

To all whom it may concern:

Be it known that I, JOSEPH W. PIPER, a citizen of the United States, residing at Lowell, in the county of Middlesex and 5 Commonwealth of Massachusetts, have invented a certain new and useful Improvement in Grates for Furnaces and Boilers, of which the following is a specification.

This invention relates to grates for furnaces and boilers such as have a divided fire-chamber.

The invention comprises independently operated fuel-supporting grates, each arranged under a separate division of the fire 15 chamber.

The object of the invention is to enable one division or compartment of the fire-box to be emptied without disturbing the fuel in the other division.

20 In the accompanying drawings Fig. 1, is a plan of the housing and the fuel-supporting or main grate in operative or fuel-supporting position; Fig. 2, a similar view with one half of the grate-bars in fuel-supporting position, the other bars being withdrawn from under the fire chamber; the upper ring E^1 is shown broken away to afford a clear view of the parts below. Fig. 3, a plan showing all the grate-bars withdrawn 25 and the upper pin-ring removed. Figs. 4 and 5, side elevations of the lower and upper pin-rings on which the grate bars are pivoted; Fig. 6, a vertical transverse section of the base of the boiler, with a front 30 elevation of the grate; Fig. 7, a vertical transverse section of the base and of the grate and of the lower part of a boiler with divided fire-chambers; Figs. 8 and 9, reversed plans of two different grate-bars.

35 40 The base B, grate section of which supports the boiler proper D and the transverse division F within said boiler D; these parts are or may be all as shown in U. S. patent granted to me Nov. 29, 1921, No. 1,398,794.

45 50 With the above-named parts will also preferably be used, the cut-off grate T with pivoted fingers t, arranged in the housing H, and the draft ring C all of which are or may be as shown in said patent and in another Patent 629,719, to Goodfellow, granted July 25, 1899.

55 Within the housing H in the lower part thereof below the grate T, I arrange the divided grate, the left-hand half consisting of fingers e^1 and the finger e^3 , pivoted to a

pin-ring E said pin-ring E resting and turning upon the bottom piece d, of the housing H, and the fingers e^1 and e^3 pivoted on pins e projecting upward from the pin-ring E, through the pin holes a, said fingers extending inwardly through openings d^1 into the fuel space.

60 In a similar manner the other half of the divided grate has a pin-ring E^1 which carries downwardly projecting pins e^5 , on which are pivoted the other half of the fingers e^2 of the divided grate, these fingers resting on the half of the pin-ring E, which has no pins on the right-hand half, and extend inwardly through the openings d^1 in 70 the housing H.

65 Each pin-ring is provided with a suitable handle S integral therewith and projecting radially therefrom, by which the corresponding pin-ring may be turned to withdraw or project the fingers of such pin-ring by means of a suitable operating bar.

75 80 Figs. 8 and 9 show the under side of both styles of grate bars for different grades of fuel and are shown cut out on their vertical concave side to allow the retraction of the adjacent bar on the side first withdrawn from the fire-chamber, also the grate bar e^3 on the ring E is longer than the other fingers or bars of the same pin-ring and is pivoted on a radial outward projection E^2 from the said ring, to enable the half of the grate 85 first retracted to make a complete stroke.

85 90 It is only by the features e^3 and e^4 , that the half of the grate first withdrawn can be retracted against the adjacent bar at rest, as shown in Fig. 2.

95 In operating the grate, the housing remaining stationary, the cut-off bars T, are first projected into the fire to sustain the burning fuel, after which the left-hand bars of the divided fuel supporting grate are withdrawn by pin-ring E, then the right-hand bars can also be withdrawn by the pin-ring E^1 .

100 I claim as my invention:—

1. In combination with a cylindrical fire-chamber having vertical transverse dividing means, separate superimposed gratings, two sets of grate bars, one set of which is pivoted to the bottom of the upper grate-ring and the other set of which is pivoted to the top of the lower grate-ring and a suitable housing for said grate-rings having ports, through which said grate bars project, each 110

set of grate bars being arranged under a separate division of said fire-chamber.

2. In combination with a cylindrical fire-chamber having vertical transverse dividing means, separate superimposed grate-rings having each its set of grate-bars to be operated successively; the set operating first

having its right-hand bar pivoted at a larger radius to effect a complete withdrawal, and the set operating last having its left-hand bar cut-away on its vertical concave side, to permit the point of the adjacent bar to retract under it in the first withdrawal. 10

JOSEPH W. PIPER.
